UNITED STATES PATENT OFFICE.

EDWARD N. JACOBI, OF MILWAUKEE, WISCONSIN, AND FRANCIS W. LAWRENCE, OF DETROIT, MICHIGAN, ASSIGNORS, BY MESNE ASSIGNMENTS, TO BRIGGS & STRATTON CORPORATION, OF MILWAUKEE, WISCONSIN, A CORPORATION OF DELAWARE.

LOCK.

Application filed February 26, 1917. Serial No. 151,011.

To all whom it may concern:

Be it known that we, EDWARD N. JACOBI and FRANCIS W. LAWRENCE, citizens of the United States, and residents of Milwaukee, 5 Milwaukee County, Wisconsin, and Detroit, Wayne County, Michigan, respectively, have invented new and useful Improvements in Locks, of which the following is a description, reference being had to the 10 accompanying drawings, which are a part of this specification.

This invention relates to locks and has for its object to provide a lock of the laminated tumbler type with means for preventing the loss of the tumbler blades when the lock barrel is removed from the case. With locks of this type the tumblers, originally alike, are ground to lie flush with the surface of the lock barrel while the key is 20 in place therein so that each tumbler blade differs from the others in the position of its key opening and no two tumbler blades are exactly alike. It is then of utmost importance that the tumbler blades be retained 25 in their original relative positions, for if two tumbler blades are transposed or if one tumbler blade is changed end for end it will project at one end or the other beyond the surface of the lock barrel and into the locking groove of the lock case to prevent the turning of the lock barrel by means of the key and the lock will, therefore, be rendered 30 inoperative. As there are a number of these tumbler blades loosely fitting within a transverse opening of the lock barrel it frequently occurs that in handling the lock 35 barrel with the key removed, as in assembling lock switches and other devices of which the lock forms a part, the tumbler blades will slide out of the lock barrel and become scattered so that it is practically impossible to reassemble them in the original order, requiring a new set of tumbler blades to be fitted to the lock barrel. The 40 present invention provides a guard engaging each of the tumbler blades in such a manner as to prevent their removal from the lock barrel when the key is removed and still not interfering with their sliding 45 movements for the proper operation of the lock.

With the above and other objects in view the invention consists in the construction and relative arrangement of certain parts

hereinafter particularly described and 55 pointed out in the claims.

In the accompanying drawings are shown various exemplifying structures embodying the invention but it is to be understood that the invention is capable of embodiment 60 in different forms.

Referring to the accompanying drawings in which like characters of reference indicate like parts in different views:

Fig. 1 is a central sectional view of a lock 65 construction embodying the present invention, the key being shown therein holding the tumbler blades in the unlocking position flush with the surface of the lock barrel and permitting the lock barrel to be 70 turned by means of the key;

Fig. 2 is a rear end view of the lock barrel with the key in place;

Fig. 3 is a longitudinal sectional view of the lock barrel with the key removed and 75 showing the tumbler blades retained in the barrel by means of the guard of this invention;

Fig. 4 is a transverse sectional view thereof on the plane of line 4—4 of Fig. 3;

Fig. 5 is a longitudinal sectional view on a plane distant from the center of a lock barrel showing a modified form of tumbler retaining means;

Fig. 6 is a transverse sectional view 85 thereof on the plane of line 6—6 of Fig. 5;

Fig. 7 is a view similar to Fig. 5 of another modification;

Fig. 8 is a transverse sectional view 90 thereof on the plane of line 8—8;

Fig. 9 is a view similar to Fig. 5 of a further modification; and,

Fig. 10 is a transverse sectional view 95 thereof on the plane of line 10—10.

In these drawings 15 indicates a lock case having a bore in which a shouldered cylindrical lock barrel 16 is revolvably mounted. A corrugated key 17 slidably fits within a correspondingly shaped key slot 18 through the lock barrel and its toothed or serrated edges fit against the opposite end walls of rectangular key openings 19 in a series of sheet metal tumbler blades 20 which form laminated tumbler means slidably positioned within a transverse tumbler opening 21 in the lock barrel and adapted to project at one end or the other into opposite grooves 22 in the lock barrel when the key 105

- is removed, thus rendering the lock barrel incapable of turning to operate a switch or other mechanism controlled by the lock. The tumbler blades 20 are held within the opening 21 against accidental removal by means of a guard pin 23 which passes across the opening 21 of the lock barrel and through the key openings 19 of all of the tumbler blades. This pin may have a driven fit within an opening provided for it in the lock barrel or it may be otherwise secured in place. When the key is removed from the lock barrel while the lock barrel is out of the case the tumbler blades are incapable of being lost as they are held in place by the guard pin 23. Being loose they may fall, as shown in Fig. 3, so as to rest on the guard pin, though they cannot be entirely removed and are thus kept in place and their proper order is preserved without necessitating great care on the part of the person handling the lock tumbler with the key removed. The presence of the guard pin does not interfere with the normal operation of the lock as the tumbler blades may freely move lengthwise the full distance required to respond to the cam action of the serrated edge of the key. The pin is furthermore positioned as shown in Fig. 2 where it does not interfere with the introduction of the key.
- In the modification shown in Figs. 5 and 6, each tumbler blade when punched is provided with an elongated notch 24 at one side thereof into which a guard rib 25 projects, said guard rib consisting of a metal strip inserted in a slot in the side of the lock barrel 16 and projecting into the opening 21 thereof a sufficient distance to engage the shoulders at the ends of the notches 20 and prevent the removal of the tumbler blade. The guard rib 25 may have a forced fit in the slot or may be held in place in any desirable manner.
- In the modification shown in Figs. 7 and 8 the tumbler blades are stamped with a projecting lug 26 at one side to enter the groove 27 formed in the side wall of the opening 21, the lock barrel 16 having its rear end portion made separate therefrom and attached to it in any desirable manner as by means of screws 28, in order that the tumbler blades may be placed therein.
- In the modification shown in Figs. 9 and 10, the tumbler blades 20 are stamped with projecting lugs 29 at each end of one side thereof and the opening 21 of the lock barrel 16 is formed with an inwardly projecting rib 30 to be engaged by said lugs. In order to assemble the tumbler blades in this form of the invention a slot 31 the width of the opening 21 forms a continuation at one end of said opening and passes through the

rib 30 and a sufficient distance beyond it to permit the tumbler blades 20 to be entered therethrough one by one until engaging the lug 29 with the guard rib 30, as seen in dotted lines in Fig. 9. When each tumbler blade is inserted in the slot 31 until its lower lug 29 is below the guard rib 30 it may be moved into the opening 21, thus engaging the guard rib 30 between its lugs 29. The tumbler blades may be threaded in place one by one and when the complete laminated tumbler block is made up they fit sufficiently close within the opening 21 to make it improbable that they should be lost by finding their way out through the slot 31.

By means of this invention a great saving in time in assembling the lock structure is effected without materially adding to the cost. The lock barrel may be handled without the necessity for care to prevent the tumblers sliding out and if it is accidentally dropped it does not necessitate the refitting with a new set of tumbler blades as has been necessary heretofore.

What we claim as new and desire to secure by Letters Patent is:

1. A lock, comprising a rotary lock barrel having a longitudinal key opening and a transverse tumbler opening, a key fitting in the key opening and crossing the tumbler opening, sheet metal tumbler blades slidably fitting in the tumbler opening and capable of sliding longitudinally therethrough for removal and each provided with an opening pierced by the key and means for preventing the loss of the tumbler blades from the lock barrel when the key is removed comprising a rib in the lock barrel projecting into the tumbler opening, said tumbler blades being provided with notches in the side thereof to receive the projecting edge of said rib without interfering with the key-produced movements of the tumbler blades.

2. A lock, comprising a rotary lock barrel having a longitudinal key opening and a transverse tumbler opening, a key fitting in the key opening and crossing the tumbler opening, sheet metal tumbler blades slidably fitting within the tumbler opening and each having an opening pierced by the key, a guard rib projecting from the side wall of the tumbler opening, and lugs projecting from one side of each of the tumbler blades for engaging the guard rib, there being a slot at one end of the tumbler opening forming an extension thereof and passing beyond the guard rib to permit of the introduction of the tumbler blades therethrough.

In testimony whereof, we affix our signatures as of the 19th day of February, 1917.

EDWARD N. JACOBI.
FRANCIS W. LAWRENCE.
